UNITED STATES PATENT OFFICE.

CHARLES MACKENZIE YOUNG, OF OTTAWA, ONTARIO, CANADA, ASSIGNOR OF ONE-THIRD TO THOMAS REGINALD ARKELL AND ONE-THIRD TO CLAUDE FEILD, BOTH OF OTTAWA, ONTARIO, CANADA.

FILM-DRYER.

1,108,306.

Specification of Letters Patent. Patented Aug. 25, 1914.

Application filed August 1, 1913. Serial No. 782,494.

To all whom it may concern:

Be it known that I, CHARLES MACKENZIE YOUNG, a subject of the King of Great Britain, residing in the city of Ottawa, Province of Ontario, Dominion of Canada, have invented certain new and useful Improvements in Film-Driers, of which the following is a specification.

The invention relates to improvements in photographic drying apparatuses, and the objects of the invention are to devise a means of rapidly drying a quantity of either films, plates or prints, or all of these together, if desirable, without being governed or hindered by atmospheric conditions in a systematic, efficient, and inexpensive way, calculated to produce uniform results at all times.

The invention consists essentially in the novel construction and arrangement of parts and devices hereinafter fully described in the following specification and the drawings that form part of the same.

In the drawings, Figure 1 is an end elevation, showing the outer casing partly in section, of a device constructed according to my invention. Fig. 2 shows a side elevation, looking in the direction of the arrow A in Fig. 1. Fig. 3 shows a side elevation of the device assembled, looking in the direction of the arrow B in Fig. 1 and showing the arrangement of the adjustable ventilating doors. Fig. 4 shows a sectional elevation taken longitudinally through the device with the cover removed. Fig. 5 shows a perspective view of one of the print-holding trays in its "open" position. Fig. 6 shows an end sectional elevation of the same tray in its closed position. Fig. 7 shows a plan view of a film holding rack, and Fig. 8 shows a side elevation in section of the same rack.

Like numerals of reference indicate corresponding parts in each of the figures.

Referring to the drawings, and especially to Figs. 1 and 4, the general principle of the invention will readily be understood. 10 indicates an outer casing, in which is mounted a length of pipe 11 preferably of iron or steel, which is provided with a plug 12 at one end, completely closing that end, and at the other end has an air and gas mixing chamber 13 of any standard or usual

design, and a gas inlet pipe 14. Along the pipe 11 at suitable intervals is arranged a series of perforations 9, adapted to permit of an even and regular egress of mixed gas, so that, when a light is applied to the outside of the pipe near these perforations, there will be a smokeless and preferably blue flame all along the outside of the pipe where the perforations are. There is a "spider" or end frame 15 and 16 at either end of the perforations, and these spiders are rotatably mounted on the pipe 11. The spiders are connected together by a drum 17, which has a plurality of longitudinally extending slits 18 arranged to correspond more or less with the perforations 9 on the pipe 11. A pulley 19 is secured to the spider 16, and may be of any suitable design, that is either flat, cambered or grooved, or if desirable, a sprocket wheel may be used in its place, as a means of imparting rotary motion to the spider 16 and the other moving parts which are secured thereto and driven thereby. 20 represents flanges which are secured respectively to the spiders 15 and 16, and these flanges may be made each in one piece, or for convenience of manufacture, I may prefer to make them in sections for a large size of machine. These flanges extend radially outward, and are each provided with a plurality of obliquely inclined grooves 21 (see Figs. 1, 4 and 8) on that side facing the opposite flange 20. The exact angle at which these grooves are to be set, I do not wish to limit myself to, since that is governed by variable circumstances, such as the power to be consumed in rotating the device, the rotary speed required, and the speed of drying which is necessary. The purpose of the grooves, is to act as a container for the print-holding trays 22 (Fig. 4 arrangement; Figs. 5 and 6 detail) or the film holding racks 23 (Figs. 7 and 8). These racks or trays are, when filled with their respective contents, slid into the grooves 21 in the end flanges 20 of the device, and I prefer to maintain them in position thereby passing a strap 24 around the outside of the device, and securing the ends of the strap together by a suitable buckle 25. It will be followed that considerable centrifugal force will be caused in each tray by the rapid rotation of the device around the

90

100

105

fixed tube 11, in the drying process, hence the necessity for an efficient means of securing the trays.

Referring to the trays 22 for holding prints, I prefer to make these (see Figs. 5 and 6) in the form of two rectangular frames 26 hinged together, each frame being covered by a strip of such material as cheese-cloth 27 on its face which, when closed, will 5 be adjacent the other frame to which it is hinged. The prints are laid flat on the cheese-cloth on one of these frames, and the other frame is closed on top of the prints, so that they are held between the two layers 10 of cheese-cloth or the like, and do not actually touch the framework.

The method of constructing the film racks 23 is shown in Figs. 7 and 8, in which a rectangular frame 28 is shown, having a 20 short groove or slit 29 at one end of the longer sides 30, and a longitudinally extending slit 31 extending nearly the whole remaining length of these sides 30. The rack I have illustrated is designed for holding 25 two films 32 side by side, at one time. The method of securing these films in the rack is by first pressing one end of the film over one of the spikes 33 which are secured to the bar 34, which bar is provided with tongues 35 slidably secured in the grooves 29, and then 30 passing the film around the adjustable member 35, so that its other end comes back to the first-mentioned end, and may be pressed over the same spike 33. This adjustable 35 member 35 is slidably secured in the grooves 31, and has a curved face 36, adapted to receive the non-sensitive side of the film, without cracking or marking it. After the film has been secured on the spike 33, the bar 34 40 is pressed tight against the end 37 of the frame 23 and is secured to it by the catch 38, which may be hinged to the end 37, or otherwise secured thereto. The adjustable member 35 is then slid along the frame to 45 tighten the film, and secured in the desired position by thumbscrews 39 or the like which extend through the slits 31. In the case of exceptionally long films being used, it may be desirable to use a spacing roller or bar 40, 50 to prevent the sides of the film from flapping and touching one another when being rotated. The spacing roller 40 is provided with thumbscrews 41, which extend through the slots 31.

55 In the operation of the device, when all the prints and films have been mounted and secured in the rotatable drum, the gas supply is turned on, and a lighted taper is passed between the arms of the end spider 60 15 or 16, to light the gas; the lid 42 of the outer cover, which is preferably hinged to the base 10, is then closed, and by means of a belt or the like (not illustrated) which passes through suitable orifices in the cover, 65 and engages the pulley 19, the drum is ro-

tated, causing a blower-like action, and sucking hot air between the trays in an outward direction. In view of the incoming gas, and the need for ventilation to keep the gas 70 alight, the permanent slot 43 is formed on one side of the cover, and on the other side, hinged doors 44 are secured, which may be opened or shut to adjust the temperature of the device.

It has been found in practice, that a very 75 few minutes' use of this device is sufficient to dry a great number of films or prints, and that by careful regulation of the gas and ventilation, the gelatin is never melted or the film or prints hurt in any way.

In order to prevent excessive end-play, I have illustrated the spacing collars 45 between the rotating drum and the frame; but as this is not an essential feature of the invention, I do not propose to be limited by 85 the exact construction of end play preventatives.

As many changes could be made in the above construction and many apparently 90 widely different embodiments of my invention within the scope of the claims, constructed without departing from the spirit or scope thereof, it is intended that all matter contained in the accompanying specification and drawings shall be interpreted as 95 illustrative and not in a limiting sense.

What I claim as my invention is:

1. A photographic drying apparatus comprising a casing, a series of rotatably mounted frames or racks in said casing and 100 means for heating said frames or racks.

2. A photographic drying apparatus comprising a casing, a rotatably mounted drum in said casing, a series of frames or racks mounted on said drum in said casing, and 105 means for heating said drum.

3. A photographic drying apparatus comprising a casing, a rotatably mounted drum in said casing, a series of frames or racks mounted on said drum in said casing, means 110 for heating said drum, means of ventilating said casing and drum, and means for regulating said ventilation.

4. A photographic drying apparatus comprising a casing, a rotatably mounted drum 115 in said casing, a series of frames or racks mounted on said drum in said casing, means for heating said drum, means of ventilating said casing and drum, and means for regulating said ventilation, said means comprising adjustable doors in said casing.

5. A photographic drying apparatus, comprising a casing, a rotatably mounted drum in said casing, a series of frames or racks mounted on said drum in said casing, means 120 for heating said drum, means of ventilating said casing and drum, and means for regulating said ventilation, and means for rotating said drum in said casing.

6. A photographic drying apparatus com-

prising a casing, a perforated pipe within said casing, a drum rotatably mounted on said pipe, a series of frames or racks mounted on said drum, in said casing, means for introducing gas to said pipe, and means for ventilating said casing and drum, and means for regulating said ventilation.

7. A photographic drying apparatus, comprising a casing with a hinged cover, said casing being formed with a slot and with adjusting doors adapted to permit of and regulate the ventilation; a drum having a series of racks peripherally mounted thereon, being rotatably mounted in said casing; and means of heating said casing and said drum.

8. A photographic drying apparatus comprising a casing, a spindle, spiders mounted on said spindle, a drum mounted on said spiders and in said casing, said drum having ventilating slots formed on its periphery; and racks secured on the outside of said drums.

9. A photographic drying apparatus comprising a casing, a hollow spindle mounted therein, means for mixing gas and air secured to one end of said spindle, a drum having racks peripherally mounted thereon rotatably secured to said spindle and in said casing; and a pulley connected to said drum and adapted to transmit rotary motion to said drum.

10. A photographic apparatus comprising a casing, a spindle, spiders and a drum on said spindle and in said casing; flanges extending radially from said spiders and said drums, said flanges having means for securing racks therebetween, said means comprising the formation of obliquely inclined slots in said flanges, and means for retaining said racks from leaving said slots by gravity or centrifugal force.

11. A photographic apparatus comprising a casing, a spindle, spiders and a drum on said spindle and in said casing; flanges extending radially from said spiders and said drums, said flanges having means for securing racks therebetween, said means comprising the formation of obliquely inclined slots in said flanges, and means for retaining said racks from leaving said slots by gravity or centrifugal force, said means comprising a belt having a buckle, secured around the outer periphery of said racks.

55 12. In a photographic drying apparatus,

a casing, a drum, heating means for said drum and casing, trays and racks adapted to be secured to said drums, said racks each comprising a rectangular frame having grooves and slots formed in its opposite sides; means for securing a film or films in said rack, said means comprising a bar having tongues at opposite ends adapted to slidably secure said bar between said sides of said frame in said grooves; spikes projecting from said bar; means for securing said bar and spikes against one end of the frame.

13. In a photographic drying apparatus, a casing, a drum, heating means for said drum and casing, trays and racks adapted to be secured to said drums, said racks each comprising a rectangular frame having grooves, and slots formed in its opposite sides; means for securing a film or films in said rack, said means comprising a bar having spikes slidably secured in said frame, means for clamping it against said frame and thereby holding the extreme ends of a film; an adjusting bar having a curved face adapted to engage approximately the center of the film, and maintain said film under tension during the drying process, means for securing said adjusting bar in any desired position.

14. In a photographic drying apparatus, a casing, a drum, heating means for said drum and casing, trays and racks adapted to be secured to said drums, said racks each comprising a rectangular frame having grooves, and slots formed in its opposite sides: means for securing a film or films in said rack, said means comprising a bar having spikes slidably secured in said frame, means for clamping it against said frame and thereby holding the extreme ends of a film; an adjusting bar having a curved face adapted to engage approximately the center of the film, and maintain said film under tension during the drying process, means for securing said adjusting bar in any desired position, a spacing bar secured intermediate of said adjustable bar and said spiked bar, adapted to prevent the sides of said film from coming in contact with one another.

In witness whereof I have hereunto set my hand in the presence of two witnesses.

CHARLES MACKENZIE YOUNG.
